UNITED STATES PATENT OFFICE.

JEREMIAH E. HELME, OF LOWELL, ASSIGNOR OF ONE-HALF TO GEORGE A. BYAM, OF CHELMSFORD, AND LARKIN T. TRULL, OF LOWELL, MASSACHUSETTS.

CIRCULAR-KNITTING MACHINE.

SPECIFICATION forming part of Letters Patent No. 375,156, dated December 20, 1887.

Application filed January 20, 1886. Serial No. 189,159. (No model.)

To all whom it may concern:

Be it known that I, JEREMIAH E. HELME, a citizen of the United States, residing at Lowell, in the county of Middlesex and Commonwealth of Massachusetts, have invented a certain new and useful Improvement in Knitting-Machines, of which the following is a specification.

My invention relates to knitting-machines of the class known as "circular spring-needle knitting machine," and has a special reference to devices which, when used in connection with the usual parts of such a machine, knit one or more courses of one color, and then one or more courses of another color, the changes being made from one color to the other automatically by severing the yarn of one color and introducing a yarn of another color.

The object of my invention is to simplify the striping mechanism and to render it less liable to get out of order, to make it less liable to leave holes at the places where the change is made from the yarn of one color to the yarn of the other color, to improve the construction and arrangement of the yarn cutting or severing devices and means for holding the end of the yarn after it is cut, to so operate such yarn severing and holding devices as that the yarn shall be cut before it is grasped by the means for holding the same, thus avoiding the putting of undue strain on the yarn thrown out of operation and the objections consequent thereon and the cutting and holding of the yarn thrown out of operation until the proper time comes for introducing it again independently of the pattern devices and directly by the rotation of the cylinder or head; also, to enable the yarn after being cut, while not being introduced into the fabric, to be held by the knife without the use of any special holding devices.

In the accompanying drawings, Figure 1 is a plan of a circular spring-needle knitting machine, the bed on which it rests, its driving-shaft and pulley, and my improvements applied thereto, a part of the bed being broken out; Fig. 2, a vertical section in the plane of the axis of the driving-shaft, all the knitting-wheels, except the pattern-wheel, being omit-

ted to avoid confusion, the driving-shaft, the 50 driving-pulley, the vertical stud about which the needle-cylinder revolves, and the beveled gear on said main shaft being in elevation, and beveled gear which engages with said last-named beveled gear being partly in elevation; 55 Fig. 3, a side elevation of the bed, the cylinder, the cutting and holding device, the finger which carries the yarn down to the cutting device, the lever which operates said finger, the spring which retracts the knife, and the lever which 50 throws it forward to open the cutting device, and the cam which operates the finger-actuating lever, a cross-section of the cam which actuates the pattern-wheel, and a cross-section of the cam which raises the sliding block on the 65 knife-lever, said section being on the line xx in Fig. 4; Fig. 4, an outside elevation of the pattern-wheel-actuating cam and of the cams which actuate the cutting and holding devices; 70 Fig. 5, an elevation of the pattern-wheel, its ratchets, the loop-wheel, the dividing-wheel, the yarn-trough, the knife-lever, the sliding block on said knife-lever, the lever which actuates said sliding block and the yarn-guides, 75 said last-named lever being attached to one of said guides, and the stand which supports the parts named; Fig. 6, a section through the middle of a part of the pattern-wheel at right angles to its axis; Fig. 7, at the left, a section through a part of the pattern-wheel in the 80 plane of its axis and at the right a similar section, on a larger scale, of the upper portion of both ratchets and the shield supported on one of said ratchets; Fig. 8, a side elevation of the knife-lever, its sliding block, stop-pin, and 85 pivot, showing the opposite side of said lever from that shown in Fig. 3; Fig. 9, a representation of a part of the pattern-wheel, the cam which operates the yarn-guides, the stud on which said cam turns, the spiral spring which 90 surrounds said stud above said cam, the tension-collar above said spring, the yarn-guides, and the lever attached to one of said yarn-guides, the line of sight in Fig. 9 being in the plane of the pattern-wheel; Fig. 10, a side 95 view of the cutting and holding devices and a part of the stud-stand of the dividing-wheel and the yarn-carrying finger, the lower part

of the knife-lever being broken away; Fig. 11, a view at right angles to that shown in Fig. 10 of a part of said stud-stand, the stud supported thereon, a part of the same being in section on the line $y-y$ in Fig. 10 to show the means of taking up the wear of the sliding part of the cutting device, showing also the pad against which the yarn is held after being cut, the line of sight in Figs. 10 and 11 being upward at an angle of about forty-five degrees; Fig. 12, a view at right angles to that shown in Fig. 10 of a part of the stud stand of the dividing-wheel, showing the top of the thread-holder, the cutting-knife, and the pad and the screw which limits the motion of the holder; Fig. 13, a vertical longitudinal section through the pawl-carrier and its supporting-rod; Fig. 14, an oblique view of the hubs and cams of the yarn-guides and a part of the lever-cam; Fig. 15, a rear elevation of the upper part of the bed, a part of the cylinder, and a rear elevation of the stationary guide; Fig. 16, a side elevation of the stationary guide and a cross-section of a part of the needle-cylinder; Fig. 17, an isometric view of the cam which operates the lever which opens the shears; Fig. 18, an elevation of the sliding block and its upward projection and supporting lever, the stand which supports said lever, the yarn-guides, and the inclined stud on which they turn.

The bed A, the driving-shaft A', the driving-pulley A², the needle-cylinder B, the spring-needles b, the stationary vertical stud B', around which the needle-cylinder revolves, the bevel-gear B², secured to said needle-cylinder in any usual manner and engaging with a bevel-gear, A³, on the driving-shaft, the push-back D, the loop-wheel E and its stand e, the dividing-wheel F and its stand f, the presser-wheel G and its stand g, the landing-wheel H and knocking-over wheel I, and the central holding-plate, J, which holds the cylinder down in place and supports on suitable brackets, h i, the landing-wheel and knocking-over wheel.

All these are of the usual construction and operation, except as hereinafter specified.

The pattern-wheel K consists of a disk provided with an annular groove, k, in its periphery and turns upon a stud, k', inclined forward at an angle of about thirty degrees from the perpendicular. Concentric with the pattern-wheel is a ratchet, L, which is prevented from moving backward by a retaining spring-pawl, l, and is adjustably secured to said pattern-wheel by screws l', which pass through arc-shaped slots k⁴ in said pattern-wheel into said ratchet, said slots being described about the center of said pattern-wheel.

The object of making the ratchet adjustable on the pattern-wheel is to enable two pattern-wheels or more to be adjusted to each other in the same knitting-machine, in order that the changes of the colors caused by each pattern-wheel may take place at the same needle.

Below the pattern-wheel is a horizontal rod, M, which slides in bearings k² on the stand k³, which

supports the pattern-wheel stud k'. Secured to the horizontal sliding rod M is a pawl-carrier, m, which consists of a metallic block provided with a hole, m', lying in the same plane with said ratchet, said hole containing a spiral spring, m², and above said spring a rod, m³, between which and the bottom of said hole said spring is compressed. The rod m³ is beveled off on its upper end to slip easily over the teeth of the ratchet L in one direction and to engage with said teeth when moved in the other direction. The rod m³ is prevented from springing out of the pawl-carrier by a stud, m⁴, driven through a slot, m⁵, in said pawl-carrier into said rod, said stud preventing the rod from turning on its axis. The end of the sliding rod M nearest the needle-cylinder is provided with a hook, m⁶, which hook engages with a groove formed in a cam-plate, N, secured on the top of the base of the cylinder. The ends of the cam-grooves in said cam-plate N are at equal distances from the center of the needle-cylinder, so that the hook which engages said cam-groove on leaving said groove is left in a suitable position to enter the other end of said groove when the cylinder revolves.

Each tooth of the ratchet-wheel L corresponds to a single course or to one revolution of the needle-cylinder—that is, the ratchet is moved one tooth at each revolution of said cylinder—and the object of the ratchet and pattern wheel is, by means hereinafter to be explained, to substitute a yarn of one color for a yarn of another color. Wipers k⁵ k⁶ are inserted in the groove k of the pattern-wheel K, being held therein by set-screws k', which turn in threaded holes parallel with the axis of said pattern-wheel and entering said groove k thrust against said wipers. The wipers project radially from said pattern-wheel and are of the same angular width (see k⁵) as one of said ratchet-teeth or as a number of such teeth. (See k'.)

On another inclined stud, O, turns a lever-cam, O', the left end, o, of which is adapted to be struck by the wipers of the pattern-wheel when said pattern-wheel is revolved, and the right end, o', of which is wedge-shaped. The lever-cam O' is rocked on the stud O when struck by the wipers, and is restored to its former position after the wiper has passed it by a spiral wire spring, o², which surrounds the stud O above said lever-cam, the lower or rear end of said spring being secured to said lever-cam O' and the front or upper end of said spring being secured to an adjustable collar, o³, which may be turned on the upper end of said stud O to increase or diminish the tension of said spring, said collar o³ being held, when adjusted, by the set-screw o⁴, which turns in said collar and thrusts against said stud, the spring being wound in such a way as to throw the left end of said lever cam upward. The hub on the lever-cam is provided with two shoulders, o⁵ o⁶, between which is placed a stop, o⁷, secured to the stand which supports

- the pattern-wheel, said stop limiting the motion of said lever-cam in both directions to keep the yarn-guides in their proper relative positions. On a stud, P, placed at about right angles to the stud O, turn the yarn-guides $p^1 p^2$. These yarn-guides have secured to their hubs $p^0 p^{10}$ downwardly-projecting cams $p^2 p^3$, which overlap each other, as shown in Fig. 14, and which are beveled away from each other at p^8 . 5
- 1c These cams are separated by the wedge-shaped right end of the lever-cam O' when the left end of said lever-cam is struck by one of the wipers to shift the position of the yarns with reference to the loop-wheel E, said hubs having secured to them, respectively, projecting arms $p^4 p^5$, to which are attached spiral springs $p^6 p^7$, the other ends of said springs being secured, as shown, to any convenient part of the frame of the machine. 15
- 20 The guide p^1 is normally held higher than the guide p^2 and directs its yarn upon the loop-wheel above the nibs q of said loop-wheel, while the other yarn-guide, p^2 , holds its yarn in the yarn-trough q' below said loop-wheel, and 25 the effect of the wipers on the pattern-wheel striking the lever-cam is, as above explained, to reverse the relative positions of the yarns, raising one yarn out of the yarn-trough onto the loop-wheel and carrying the thread previously on the loop-wheel down into the yarn-trough, so that when yarns of different colors are used the color of the fabric is changed by the shifting of the yarn-guides, only that color appearing in the fabric at any time which belongs to the yarn at that time passing over the 35 loop-wheel.
- The yarn trough q' is provided with a bent arm, q'' , by means of which it is supported on the stand e of the loop-wheel. 40
- To prevent making holes in the fabric at the point where the color is changed, it is necessary that a few stitches should be made in the yarn to which the change is made before the other yarn is cut. This object is accomplished 45 by the shape of the right end, o' , of the lever-cam O' and the shape of the cams $p^2 p^3$. The right end, o' , of the lever cam is wedge-shaped in cross-section; but the sides of the wedge are not straight, but curved to give a blunt point 50 to the wedge, which, as it first enters between the cams $p^2 p^3$, separates them quickly and moves the yarn-guides rapidly for a distance. The faces of the cams $p^2 p^3$ are nearly parallel 55 with the axis of the hubs, to which they are attached for a short distance from the lower ends of said cams, so that after the wedge o' has passed entirely between said cams its effect in separating said cams is very gradual, and at this time the change is being made from 60 one yarn to the other and both yarns are being knit into the fabric. Immediately, however, the sides of the wedge o' come into contact with the upper parts of the faces of said cams, these upper parts being at a greater angle with the 65 axis of the stud P than the lower parts of said cams, so that the yarn-guides are then moved rapidly.

When the change is made from one yarn to the other at the loop-wheel by the above-described movement of the yarn-guides, it is necessary that the yarn thrown out of the loop-wheel should not reach the dividing-wheel and the wheels beyond it. The yarn which runs through the yarn-trough is therefore severed just beyond said yarn-trough and held in a position to be again introduced into the fabric when the yarn-guides are restored to their normal position. 70

The holding and cutting devices are supported upon the stud-stand f of the dividing-wheel F, and so also is the yarn-carrying finger f^1 , which carries the yarn downward to the knife. The cutting device consists of a stationary knife, f' , secured on said stand f , and a sliding yarn-holder, f^2 , which in sliding by 85 said knife acts in connection therewith substantially like a pair of shears, into which the yarn is pushed by the front end of the yarn-carrying finger f^3 , pivoted upon the top of said stand f , said front end being normally raised 90 by the pressure of a spring, f^4 , upon its rear end, and being thrown downward by the bent lever f^5 , pivoted upon said stand. The upper front end of said last-named lever bears against the under side of the rear end of said yarn-carrying finger, as best shown in Fig. 3, and the lower end of said bent lever is raised by 95 the cam N running under it once in every revolution of the needle-cylinder. The yarn is prevented from dropping below the stationary knife f' by the rest f^6 , which projects from the lower part of the edge of said stationary knife and has a horizontal upper surface, as shown in Fig. 10, and the yarn to be cut is carried down to the rest f^6 by the finger f^3 , in 100 order that the yarn, after being cut, may be held always at the same height, and thereby carried onto the same part of the loop-wheel, when the yarn-guides are again shifted in order that the joining or overlapping of the 105 yarns at the place where the change is made in the fabric may always be of the same length. 110

The means of supporting the sliding yarn-holder and knife f^2 is shown in Figs. 10 and 11. Two screws, $f^{11} f^{12}$, the flat under sides of the heads $f^{13} f^{14}$ of which rest against the front side of said knife f^2 , enter the stand f , to hold the horizontal part f^{15} of the shank of said knife in a groove in said stand, said horizontal shank being pressed against the head of the screw f^{12} nearest the needle-cylinder by a spiral spring, f^{16} , (shown in Fig. 11,) inserted in a hole, f^{17} , drilled in said stand f , and thrusting a small block, f^{18} , which slides in said hole, against the rear face of said shank. When 120 the knife f^2 is worn by sliding on the knife f' , it may be set up against said last-named knife by turning up the screws $f^{11} f^{12}$. The motion of the holder and knife f^2 toward the needle-cylinder is limited by a stop-screw, f^{19} , which turns in a rib, f^{20} , on the stand f , toward the upwardly-projecting rear part, f^{21} , of the shank of said holder and knife f^2 , said stop-screw 125 being adjusted to prevent the knife f^2 from 130

striking the needles *b*. The stationary knife *f'* is held rigidly on the stand *f* by a screw, *f²²*, which passes through said knife into said stand, and by a steady-pin, *f²³*, which projects 5 from said knife and enters a hole in said stand.

The pad-holder consists of a piece of sheet metal, *F'*, having the end nearest the needle-cylinder bent forward parallel with the cutting-10 edge of the knife *f'*, the pad *F²* being a piece of leather, felt, or similar material slotted to receive the bent end of the pad-holder *F'* and retained thereon by friction. The pad-holder is adjusted to position by means of an adjusting-screw, *f²⁴*, turning in said rib *f²⁰* and thrusting against the outer end of said pad-holder, which outer end is bent forward at right angles to the body of the pad-holder to receive the thrust of said last-named screw. The pad-15 holder, when adjusted with its front end near the edge of the cutting-knife *f'* and parallel with said edge and farther from the needle-cylinder than said edge, is rigidly held by a set screw, *f²⁵*, passing through a slot, *f²⁶*, in 20 said pad-holder into the stand *f*, said pad-holder being prevented from rocking on said stand by studs *f²⁷* *f²⁸*, which project from said pad-holder and rest upon the top of said stand.

The yarn-holder or movable knife *f²* is 25 pushed toward the needle-cylinder to admit a yarn between said last-named knife and the stationary knife *f'* by the cam *N²* striking against the side of a block, *R*, which slides up and down, as hereinafter explained, on the 30 lower arm of a lever, *R'*, pivoted at *r* in a stud, *r'*, projecting from the stand *f*, said cam *N²* pushing the lower end of said lever *R'* outward or away from the needle-cylinder and causing the upper end of said lever *R'* to press against 35 the rear end of said knife *f²*.

The knife *f²* is drawn outward past the knife *f'* by a spring, *f⁸*, connected to said rear end and to a pin, *f⁹*, projecting from said stand *f*, cutting the yarn (placed between said knives 45 by the yarn-carrying finger) and then holding the end of the yarn nearest the yarn-trough between said knife *f²* and the pad *F²*. The cams *N'* *N²* are so arranged with reference to each other and to the levers *f⁵* and *R'* that the 50 front end of the yarn-carrying finger is thrown down immediately upon the movement of the knife *f²* toward the needle cylinder.

It is to be particularly noticed that the pad, which constitutes one of the essential elements 55 of the yarn-holding device, is located beyond or in the rear of the yarn severing or cutting device, so that the yarn must be completely severed before it can be grasped by the yarn-holding device. This is an important feature 60 of my invention, since it obviates the objections consequent upon grasping and holding the yarn before effecting the cutting or severing of the same. In my invention, the cutting of the yarn being accomplished before the end is 65 grasped by the holding devices, no undue strain is put upon the strand thrown out of operation, no matter how rapidly the machine

may be running, and all liability of forming a hole in the fabric, or of having the yarn broken by the landing or knocking-over wheel, or of meeting with other difficulties heretofore experienced from grasping and holding the yarn before the cutting operation takes place, is entirely obviated.

As the cams *N'* *N²* pass the lower ends of the 75 levers *f⁵* *R'* once in every course, or once in every revolution of the needle-cylinder, some arrangement is necessary to prevent the opening of the yarn-holder *f²* *F²* until the desired 80 number of courses have been knit from the yarn then running on the loop-wheel. Accordingly the sliding block *R*, after passing the cam *N²*, is lifted by the cam *N'* high enough to be out of reach of the cam *N²* during the next revolution of the needle-cylinder, the upward 85 motion of said block *R* on said lever *R'* being limited by a stop pin, *r²*, which projects from the side of said lever *R'*, the rear side, *r³*, of said sliding block being made convex, in order that it may be held in either of its positions 90 by the pressure of a spring, *f⁷*, supported on said stand *f* and pressing against said convex side above or below the greatest convexity thereof. Said sliding block *R* is provided with an upward projection, *r⁴*, which has an 95 inward and outward inclination, *r⁵*, on the top of the same, and which, when the change is made from one color to the other, is struck by the projecting arm *p⁵* of the yarn-guide *p*, so that when the yarn-guides are shifted by the 100 action of the pattern-wheel, as above described, the arm *p⁵* is thrown inward or outward, as the case may be, over said incline and forces said block downward into a position to be struck by the cam *N²* during the same revolution of the needle-cylinder.

A stationary guide, *S*, is secured to the bed of the machine, and consists of a strip or piece of metal, the upper edge of which is inclined upward in the direction of the rotation of the 110 needle-cylinder, the lower part of which edge is preferably arranged below the knocking-over wheel, (although the guide may be placed at some distance from the knocking-over wheel,) and the upper part of which edge 115 reaches over the tops of the needles, the object of this guide being to hold up the ends of the yarus and prevent them from being looped into the fabric, the fabric being knit inside out, and the intention being to make the loose 120 ends of the yarn show only on the wrong side of the fabric.

The capacity of the pattern-wheel may be doubled or increased to any less amount by the use of the shield, hereinafter described, with 125 a supplementary ratchet, *L'*, concentric with said pattern-wheel, and with the ratchet *L*, turning loosely on the stud *k'*, which supports said pattern-wheel. The ratchets *L* *L'* have an equal number of teeth and have independent pawls, the pawl *m'* being precisely like the pawl *m³* and supported in the pawl-carrier in the same manner and forced into engagement with the ratchet-teeth by similar means.

The stud k' , on which the ratchet L' turns, is provided with an annular collar, k^8 , in front of the ratchet L , which keeps the two ratchets out of contact with each other and prevents the ratchet L from being turned by frictional contact with the ratchet L' . A washer, L^2 , of leather, cloth, or similar material, surrounds the stud k' in front of the ratchet L' , and is pressed against the hub of said last-named ratchet by a metallic washer, l^2 , and a nut, l^3 , turns on the end of said stud, and compresses said washer L^2 to prevent the ratchet L' from jumping or moving more than one tooth at a time.

15. A shield, L^3 , consisting of an arc shaped strip of sheet metal and provided with a stem, L^4 , by means of which it is fastened to the ratchet L' , and held over a part of the teeth of the ratchet L in such a manner that when said shield is carried by the revolution of the ratchets below the ratchet-wheels it prevents the pawl m^3 from engaging with the teeth of the ratchet L until by the revolution of the ratchet L' the shield is carried beyond the pawls, whereupon the pawl m^3 will again come into engagement with the teeth of the ratchet L . Any desired number of such shields may be used, and the shield may be arranged upon the ratchet L' in such a manner as to disengage the pawl m^3 from the ratchet L at the time when the yarn-guides are being held out of their normal position by a wiper, or at the time when the wipers are not in actual contact with the lever-cam O' , with the effect of introducing a greater number of courses of the ground-color or a greater number of courses of the striping-color.

It will be seen that by varying the number of wipers in the pattern-wheel the color of the fabric may be varied as often as desired—as, for instance, by using a wiper for every other tooth of the ratchet-wheel the color of the fabric would change at each course; also, that the width of the horizontal stripe of either color 45 will depend on the relative angular distance covered by the wipers to the angular distance in which no wipers are used; also, that the wipers are adjustable with reference to the other wipers on the same pattern-wheel to bring them to act on the yarn-guides at the same needles of the cylinder by loosening the screws which secure them in the groove of the pattern-wheel and sliding them in said groove.

I claim as my invention—

55. 1. The combination of a stationary knife, a movable knife adapted to pass by the cutting-edge of said stationary knife and to form with said stationary knife a pair of shears, and a pad located beyond or in rear of the shears and adapted to be pressed upon by said movable knife after the same has passed the edge of the stationary knife to hold a yarn previously cut by said shears, substantially as and for the purposes set forth.

65. 2. The combination of a stationary knife provided with a projecting yarn-rest, f^6 , a movable knife adapted to pass by the cutting-

edge of said stationary knife and to form with said stationary knife a pair of shears, and a pad located beyond or in rear of the shears and adapted to be pressed upon by said movable knife after the same has passed the edge of the stationary knife to hold the yarn previously cut by said shears, substantially as and for the purposes set forth.

75. 3. The combination of a stationary knife, f' , provided with the projecting yarn-rest, f^6 , a movable knife adapted to pass by the cutting-edge of said stationary knife and to form with said stationary knife a pair of shears, and pad-holder F' , provided with pad F^2 , said pad being located beyond or in rear of the shear-point of the knives and adapted to be pressed upon by said movable knife after the same has passed the edge of the stationary knife to hold the yarn previously cut by said knives, substantially as and for the purposes hereinbefore set forth.

80. 4. The combination of a movable knife and a stationary knife provided with a rest to prevent a yarn placed between said knives from falling below the cutting-edge of said stationary knife, and a yarn-carrying finger adapted to carry a yarn between said knives and onto said rest, and a pad secured to said stationary knife parallel with the edge of the same, as and for the purpose specified.

85. 5. The combination of the needle-cylinder, a cam-plate secured thereto, provided with a cam-slot, a rod sliding in suitable bearings and provided with a hook adapted to enter said cam-slot, a pawl-carrier secured to said rod and adapted to have a reciprocating horizontal motion when said needle-cylinder is revolved, a pattern-wheel, a suitable stud on which said pattern-wheel is supported and revolved, a ratchet secured to said pattern-wheel concentrically therewith, another ratchet-wheel concentric with said pattern-wheel and turning on said stud independently of said pattern-wheel and first-named ratchet, independent pawls supported in said pawl-carrier, springs thrusting said pawls into engagement with said ratchets respectively, and a shield secured to said independent ratchet and overlapping one or more of the teeth of said secured ratchet, as and for the purpose specified.

90. 6. The combination of the needle-cylinder, the cam-plate secured thereto and provided with a cam-slot, a rod sliding in suitable bearings and provided with a hook which enters said cam-slot and is given a reciprocating motion by the revolution of said needle-cylinder, a pawl-carrier secured to said rod, a pawl supported in said carrier, a pattern-wheel provided with wipers, a ratchet secured to said pattern-wheel concentrically therewith, a pivoted lever-cam, one end of which is adapted to be struck by said wipers as said pattern-wheel is revolved, the other end of which lever-cam is wedge-shaped in cross-section, yarn-guides provided with hubs and with cams having inclined edges which overlap each other, the lower ends of said cams being separated and

said cams being adapted to be pushed apart by the last-named end of said lever-cam to shift said yarn-guides, and springs to draw said cams toward each other, as and for the purpose specified.

7. The combination of the shears, consisting of the stationary knife and the movable knife and a spring operating said movable knife to close said shears, with a knife-lever, the upper end of which bears against said movable knife, a block sliding on the lower arm of said lever, the needle-cylinder have a cam secured thereto, adapted to strike the face of said block nearest the needle-cylinder when said block is in its lowest position and said cylinder is revolved, another cam secured to said needle-cylinder and caused by the revolution of said needle-cylinder to slide said block upward on the lower arm of said knife-lever to a position higher than said first-named cam, and means, substantially as described, for holding said block in its raised position, as and for the purpose specified.

8. The combination of the shears, consisting of the stationary knife and the movable knife and a spring operating said movable knife to close said shears, a knife-lever, the upper arm of which bears against said movable knife, a block sliding on the lower arm of said knife-lever, the needle-cylinder, a cam secured thereto, adapted to strike the face of said block nearest said cylinder when said block is in its lower position and said cylinder is revolved, another cam secured to said needle-cylinder and adapted by the revolution thereof to slide said block upward above said first-named cam, said block having a convex side, and a spring pressing upon said convex side and adapted to hold said block in either of said positions by pressing said convex side above or below the greatest convexity thereof, as and for the purpose specified.

9. The combination of the shears, the knife-lever, the needle-cylinder, two cams secured to said needle-cylinder, a block adapted to slide on the lower arm of said knife-lever into a position to be struck by one of said cams to open said shears and to be raised by the other of said cams above said first-named cam, and having an upward projection inclined inwardly and outwardly on the top thereof, as described, yarn-guides provided with concentric hubs adapted to be turned upon an inclined stud which supports said guides to change their relative heights, said stud, and means for turning said hubs, one of said yarn-guides having secured to its hub a projecting arm adapted, when said guides are shifted in either direction, to strike upon the inclined top of the projection on said sliding block and to move the same into a position to be struck by one of the cams on said needle-cylinder, as and for the purpose specified.

10. The combination of the stationary knife, the stand to which the same is secured, said stand being provided with a groove, another knife having a shank placed within said groove and adapted to slide therein, screws turning in threaded holes in said stand, the under sides of the heads of said screws being flat and bearing upon said cam, said stand having a hole drilled therein at right angles to the plane of said movable knife and near the cutting-edge thereof, a spring placed in said hole, and a block sliding in said hole and pressed outward by said spring against said movable knife, as and for the purpose specified.

JEREMIAH E. HELME.
